(57) **CLAIM**

The original design for an interface connector receptacle, as
shown and described.

DESCRIPTION

FIG. 1 is a front side of perspective view of an interface
connector receptacle showing my new design;
FIG. 2 is a rear side of perspective view thereof;
FIG. 3 is a front elevational view thereof;
FIG. 4 is a rear side elevational view thereof;
FIG. 5 is a top plan view thereof;
FIG. 6 is a bottom plan view thereof; and,
FIG. 7 is a right side view thereof.
